(57) **CLAIM**

The ornamental design for a cart, as shown and described.

DESCRIPTION

FIG. 1 is a perspective view of a cart;
FIG. 2 is a front elevation view thereof;

FIG. 3 is a rear elevation view thereof;

FIG. 4 is a top plan view thereof;

FIG. 5 is a bottom plan view thereof; and,

FIG. 6 is a right elevation view thereof; the left elevation view
is a mirror image thereof.

The broken lines shown in the drawings illustrate portions of
the cart that form no part of the claimed design.
